UNITED STATES PATENT OFFICE.

WILFRED LEWIS, OF HAVERFORD, PENNSYLVANIA, ASSIGNOR TO THE TABOR MANUFACTURING COMPANY, OF PHILADELPHIA, PENNSYLVANIA, A CORPORATION OF PENNSYLVANIA.

VIBRATOR.

1,245,603.

Specification of Letters Patent.

Patented Nov. 6, 1917.

Application filed June 10, 1915. Serial No. 33,349.

To all whom it may concern:

Be it known that I, WILFRED LEWIS, a citizen of the United States of America, residing in Haverford, in the county of Montgomery, State of Pennsylvania, have invented certain new and useful Improvements in Vibrators, of which the following is a true and exact description, reference being had to the accompanying drawings, 10 which form a part thereof.

My present invention relates to fluid pressure devices commonly called vibrators such as are employed in the metal founding art to set a pattern into rapid vibration relative 15 to the mold in the pattern drawing operation, to annul the adhesion, so to speak, between the mold and pattern without appreciably enlarging the mold.

As practically constructed such vibrators 20 comprise a barrel or cylinder having closed ends which serve as anvils to receive the impact of the hammer formed by a piston working in the cylinder or barrel, and reciprocated with great rapidity by the pressure 25 fluid, ordinarily compressed air, which is alternately admitted to, and permitted to exhaust from the cylinder. The piston or hammer element of such a vibrator moves back and forth with great rapidity, the 30 number of blows struck per minute by the hammer commonly running from eight to twenty thousand, depending on the size and design of the vibrator. In consequence of 35 the force and high frequency of the blows struck by the piston, great difficulty has been experienced in preventing the separable parts of the vibrator from working loose in operation, and in securing the strength necessary to prevent rupture of the 40 instrument.

The object of my present invention is to overcome the difficulties referred to, and this I accomplish by providing a suitable resilient cushion for the metallic parts serving as the anvils receiving the impact of the vibrator piston. The cushion material which I now consider preferable, from a practical standpoint, is compressed cork, though other materials may be employed 45 for this purpose.

The various features of novelty which characterize my invention are pointed out with particularity in the claim annexed to and forming a part of this specification.

50 For a better understanding of the invention,

however, and the advantages possessed by it, reference should be had to the accompanying drawings and descriptive matter in which I have illustrated and described the preferred embodiment of my invention.

60

Of the drawings:

Figure 1 is a longitudinal section of a vibrator constructed in accordance with the present invention; and

Fig. 2 is a transverse section taken on the 65 line 2—2 of Fig. 1.

In the drawings, A represents the barrel or cylinder body of the vibrator, and B the piston working therein. As shown, there are two inlet ports A² and A³ leading from 70 a common supply passage A⁴ to the cylinder space A' within the member A. The barrel A is also formed with two sets of exhaust ports A⁵ and A⁶ respectively. The piston B, which is but little shorter in length than the cylinder space, is formed with circumferential grooves B² and B³ which communicate through radial passages B' with a corresponding axial passage B⁴ extending 75 into the piston one from each end. Extending across the ends of the cylinder space A' are washer like anvil members D and D' ordinarily formed like the piston B of tempered steel. These are held in place by cap members C and C' screwed on to the threaded ends of the cylinder body A and forming the ends of the vibrator cylinder proper. As shown, the anvil members D and D' are provided on their outer ends with central 80 bosses D² which register with central chambers C² in the cap members C and C'. Surrounding each boss D² is a washer like cushion E of a suitable resilient compressible material. As already stated, I consider 85 compressed cork to be superior to any other substance now known to me out of which to form the cushions E. Each cushion which is of the same outside diameter as the corresponding anvil member D or D', is confined 90 at its edges between the boss D² and the inner wall of the corresponding cap member C or C', and at its sides between the anvil D and the end wall of the cap member C. The chambers C² in the cap members are 95 filled with lubricating material H or rather felt impregnated with lubricating material. As shown the cap member C is formed with apertured ears C⁴ by which the vibrator may be clamped to a pattern or to the pattern plate of a molding machine or the like.

110

In Fig. 1 the piston B occupies an intermediate neutral position. When the vibrator is not in operation the piston B is prevented occupying this intermediate neutral position 5 by a spring F seated at its ends in sockets formed in the washer D' and the adjacent end of the piston B. This spring holds the piston B against the anvil member D. When the piston B thus engages the anvil 10 member D, the left hand end of the cylinder space A' is connected to the supply passage A⁴ through port A², channel B², and the corresponding radial port B' and axial passage B⁴. At the same time the right hand 15 end of the cylinder space is connected to the exhaust ports A⁶ through the groove B³ and the corresponding radial port B' and axial passage B⁴. With the parts in the position just described, the pressure fluid, when supplied 20 to the passage A⁴, moves the piston B to the right, and this moves the groove B² out of register with the port A² and into register with the exhaust passage A⁶, and at the same time moves the groove B³ out of register 25 with the exhaust passages A⁶ and into register with the supply port A³, whereupon the return movement of the anvil is brought about. This port arrangement of the apparatus 30 and the valve action of the piston causes the piston to reciprocate at high speed so long as the compressed air or other pressure fluid is supplied to the inlet passage A⁴, as will be readily apparent to those skilled in the art, especially as the vibrator shown 35 differs from those which have long been in common use, only in the provisions made for cushioning the anvil.

I have found by an extended practical use 40 of my invention that the provision of the cushion anvils as described markedly decreases the liability of the parts of the device working loose, and greatly decreases the tendency of the device to rupture under the strains and stresses due to long continued 45 operation. At the same time, the cushioning of the anvils does not appear to materially impair or change the effectiveness of the vibrator in freeing patterns from molds, or

in like uses. My practical experience leads me to believe that the cushions formed of compressed cork or other suitable compressible material, are so long lived as to be practically indestructible when made with sufficiently large contact surfaces, as they readily may be. I attribute the fact that the compressed cork cushions which I have used do not disintegrate or char in operation, to the fact, that the cork is porous and the fine pores contain a considerable amount of air which actually perform a major portion 60 of the cushioning function. Ordinarily the vibrators are double acting as shown, but when made single acting a cushioned anvil will obviously be needed at one end only of the cylinder space. 65

While in accordance with the provisions of the statutes I have illustrated and described herein the best form of my invention now known to me it will be apparent to those skilled in the art that changes may be 70 made in the form of my invention without departing from its spirit, and that some features of my invention can be used in some cases without a corresponding use of other features of the invention. 75

Having now described my invention, what I claim as new and desire to secure by Letters Patent, is:

A vibrator of the kind described comprising a metallic cylinder formed with a 80 cylinder space and with a lubricant receiving cavity smaller in diameter than, and centrally located in one end wall of said space, a reciprocating piston working in said space, a movable metallic anvil member in said space, said anvil member being formed with a central aperture and with an annular projection on its outer side adjacent, and in register with said cavity and a washer of compressible resilient material 90 surrounding the annular projection of said anvil member and interposed between the body of the latter and the end wall of said cylinder space. 85

WILFRED LEWIS.
